UNITED STATES PATENT OFFICE.

HENRY NOEL POTTER, OF HALENSEE, GERMANY, ASSIGNEE TO GEORGE WESTINGHOUSE, OF PITTSBURG, PENNSYLVANIA.

HEATER CUT-OUT FOR ELECTRIC LAMPS.

SPECIFICATION forming part of Letters Patent No. 685,488, dated October 29, 1901.

Application filed August 15, 1900. Renewed September 6, 1901. Serial No. 74,577. (No model.)

To all whom it may concern:

Be it known that I, HENRY NOEL POTTER, a citizen of the United States, residing at Halensee, in the Kingdom of Prussia and Empire of Germany, have invented a new and useful Improvement in Heater Cut-Outs for Electric Lamps, of which the following is a specification.

My invention relates to electric lamps of the type in which the illuminating body or glower is a conductor only when hot; and it has particular reference to the means for cutting out of circuit the heaters employed for raising the temperature of the glowers in such lamps to the conducting-point.

The object of my invention is to provide an electromagnetic heater cut-out which will be operative under the action of a comparatively small percentage of the glower-current without unduly increasing either the size of the cut-out coil or the expense of its manufacture and at the same time avoiding the injuries caused by excessive heat due to the consumption in the coil of an excessive quantity of energy. With these ends in view I have devised the means shown in the accompanying drawings, in which—

Figure 1 is a diagram of a constant-potential circuit in which a plurality of lamps are connected in series. Fig. 2 is a diagram of the essential features and circuits of a lamp constructed in accordance with my invention.

I have found in practice that under certain conditions of operation, more particularly those which obtain in a constant-potential circuit supplying a plurality of lamps in series, such as are employed in lighting systems for rural and suburban districts, there is a time during the lighting of the lamps in the circuit when both the heater-current and the glower-current of one or more lamps will be thrown upon the glowers and ballasts of such lamps as have already started, thereby endangering or destroying such glowers and ballasts, particularly the latter, since they are not capable of withstanding an excessive current-overload. In order to overcome the difficulties incident to such condition and operation, I propose to employ a sensitive heater cut-out which will serve to interrupt the heater-circuit before the glower takes suf-

ficient current to render the combined heater and glower current of the particular lamp thus operating dangerous to the lamps of the series already in operation.

Referring now particularly to the drawings, the circuit 1 is supplied with energy either directly or through a transformer from a main circuit 2, fed by a constant-potential generator 2^a. The lamps 3, of which ten are shown in Fig. 1, will obviously be designed individually for such voltage that the number connected in series will be adapted to the voltage supplied to the circuit either directly or indirectly from the circuit 2. The glower 4 of each lamp is supplied with current through a ballast device 5 and is heated to conducting temperature by a suitable heater 6, as is usual in this class of lamps.

The cut-out for the heater-circuit comprises a magnet-winding 7, a core 8 therefor, and a movable contact member 9, that normally rests in contact with a stationary contact-terminal 10 and is moved into contact with a second stationary contact-terminal 11 when the magnet is energized. The contact-terminal 10 is connected to one terminal of the heater 6 and the contact-terminal 11 to a suitable point intermediate the ends of the winding 7. The two parts 12 and 13 of the winding 7, between which the terminal 11 is connected, may be considered as separate coils connected together or as parts of a single winding. One terminal of the winding 7 is connected through the ballast device 5 to one terminal of the glower. The other terminal of the winding is connected to the movable member 9 of the cut-out. It will be readily seen that when the glower is raised to conducting temperature by means of the current traversing the heater current will flow through the entire coils 7, and by reason of the length and consequent resistance of such coil the amount of current will not be sufficient to endanger the other lamps in this series, but the small amount of current is sufficient to lift the member 9 into engagement with the stationary contact-terminal 11, and when brought to that position the part 12 of the winding 7 will be short-circuited.

It has been found in practice to be feasible to employ a magnetic cut-out of the usual

type which will interrupt the heater-circuit upon the passage of one-half the full glower-current and which will not become unduly heated nor be extremely wasteful of energy 5 when traversed by the entire current of the glower; but an attempt to employ a cut-out which will interrupt the heater-circuit when traversed by a small percentage, even as high as twenty-five per cent., of the normal glower- 10 current involves difficulties on account of the size of the coil necessarily employed and the consequent expense of manufacture and the heating in use. With my present arrangement the heater-circuit is interrupted before 15 the glower takes sufficient current to render the combined heater and glower current dangerous to other lamps in the series, and the short-circuiting of the part of the magnet-winding leaves only sufficient winding in circuit to maintain the heater-circuit in open condition.

My invention is not necessarily limited to use in connection with lamps operated in series in a constant-potential circuit, and I 25 therefore desire it to be understood that variations in this respect, as well as in others, may be made without departing from the invention.

I claim as my invention—

30 1. In an electric lamp of the type described, the combination with a glower and a heater therefor, of a heater cut-out having two coils primarily connected in series with the glower

and having means for cutting out one of said coils after the heater is cut out. 35

2. In an electric lamp of the type described, the combination with a glower and a heater therefor, of a heater cut-out comprising two coils connected to form a single winding for breaking the heater-circuit and means for 40 short-circuiting one of said coils after the heater-circuit is broken.

3. In a constant-potential electric circuit, a plurality of electric lamps of the type described connected in series each of which has 45 a heater cut-out comprising a magnet and means for short-circuiting a part of said winding immediately after the heater-circuit is interrupted.

4. In a constant-potential electric circuit, 50 a plurality of lamps connected in series each of which has a glower and heater and a heater cut-out comprising an actuating-magnet, a movable member and two coöperating contact-terminals connected respectively to one 55 heater-terminal and to an intermediate point in the magnet-winding, whereby the entire magnet-winding is utilized to break the heater-circuit and a portion of the same is immediately thereafter short-circuited. 60

In testimony whereof I have hereunto subscribed my name this 31st day of July, 1900.

HENRY NOEL POTTER.
